UNITED STATES PATENT OFFICE.

BYRON O. SHORT, OF PIERCE CITY, MISSOURI, ASSIGNOR OF ONE-THIRD TO JOE J. MANLOVE AND ONE-THIRD TO JAMES A. WRIGHT, BOTH OF PIERCE CITY, MISSOURI.

INTERNAL-COMBUSTION ENGINE.

1,275,616.

Specification of Letters Patent. Patented Aug. 13, 1918.

Application filed September 8, 1915, Serial No. 49,587. Renewed June 3, 1918. Serial No. 238,036.

To all whom it may concern:

Be it known that I, BYRON O. SHORT, a citizen of the United States, residing at Pierce City, in the county of Lawrence and State of Missouri, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to internal combustion engines, and more particularly to an engine of this character wherein a plurality of pistons oscillate through sector cylinders, and wherein charges are taken into the cylinders at either side of the pistons compressed, fired and exhausted upon subsequent oscillations thereof.

It is the object of the present invention to provide an engine of this character wherein a great number of the parts employed in the operation of the ordinary combustion engine are eliminated to provide a more substantial and compact engine, and whereby greater efficiency is accomplished due to the elimination of such parts and a consequent reduction of friction.

In accomplishing this object I have provided the details of structure hereinafter described and illustrated in the accompanying drawings, wherein:

Figure I is a vertical cross-section of an engine embodying my invention, taken on the line I—I of Fig. III.

Fig. II is a plan view of the engine particularly showing the intake and exhaust manifolds and the valve operating mechanism.

Fig. III is a central, vertical longitudinal section of the engine.

Fig. IV is an end view showing the connection of the piston rocker arm with the power or drive shaft.

Referring more in detail to the parts:

1 designates a housing as a whole, which carries the operating parts of the engine, and which comprises a lower section 2 which contains the power pistons and an upper section 3 which is removably secured to the lower section 2 and carries the valve

mechanism and parts working in conjunction therewith.

The lower housing section 2 is here shown to contain two semi-spherical explosion chambers, each divided by a piston into right and left compartments, designated by numerals 4—4' and 5—5', provided with pistons 6 and 7 that are rigidly mounted on and extending in the same plane from a rocker shaft 8 and are adapted to oscillate within their respective chambers through a predetermined arc which is somewhat less than the limits of the said chambers; the shaft 8 being extended the length of the engine housing and revolvably mounted in bearings 10—11—12 in the lower section and secured therein by the overlying bearing portions 14 of the upper section 3.

The rocker shaft 8 is extended somewhat beyond the housing at the rear of the engine 75 and is there provided with a laterally extending crank arm 16 to which is pivotally secured a connecting rod 17 which in turn connects with the crank arms 18 of a power shaft 19; the said shaft 19 being revolvably mounted in bearings 20—21 and extends parallel with and beneath the housing section 2 and carries a fly wheel 22.

With this arrangement of parts it will be seen that the oscillating motion of the pistons, later described, within their cylinders imparts a like motion to the crank arm 16, which, in turn, causes a reciprocation of the connecting rod 17 to cause rotation of the power shaft.

In order that the fuel charges may be admitted to and exhausted from the explosion chambers I have provided the intake manifold 24 and exhaust manifolds 25—25'; the intake manifold leading from a carburetor as shown or any suitable source of fuel supply, and comprising branch tubes 26—26' which open into compartments 4 and 4' respectively of the forward explosion chamber, and having like branches 27—27' opening into opposite compartments 5—5' of the rear explosion chamber; all branches leading to the main inlet manifold 24 to provide for an equality of distribution to the various explosion chambers.

The exhaust manifolds 25—25' likewise lead from each explosion chamber to a muffler (not shown) at the rear of the engine; the manifold 25 being placed adjacent the intake tubes 26—27 and has laterally turned 110

tubes 28—28' opening into the chambers 4—5 respectively. The manifold 25' is likewise provided with branch tubes 29—29' opening into the cylinder compartments 4'—5' respectively.

In order that the fuel charges may be taken into and exhausted from the explosion chambers at proper intervals, I have provided each of the intake and exhaust openings with 10 valves 30 of the ordinary "puppet" type, comprising valve disks 31, having beveled circumferential surfaces 32 for seating within similarly tapered valve seats 33, and which are carried on valve stems 34, that are 15 extended upwardly through and somewhat beyond guide bearings 35 in the manifold wall and are provided with end nuts 36; the valves being normally held closed, by means of coil springs 37 wound about the external 20 portion of the valve stems and bearing against the end nuts 36 and guide bearings, except when actuated by the intermittent cam motion later described.

To provide for the actuation of the valves 25 at regular and proper intervals with respect to the piston movement, I have provided a cam shaft 40 which extends parallel with the rocker shaft 8 and is centrally located with respect to the valves 30, and is revolu- 30 bly mounted in the central bearings 41 of standards 42 formed integrally with the housing member 3.

Extending laterally from the standards 42 are side arms 43, having spaced end ears 44 35 between which are pivotally mounted rocker arms 45; the rocker arms being arranged in pairs and a rocker being provided for each valve, and each having an outer arm 46 which overlies its respective valve stem and 40 an inner arm 47 which carries a roller 48 for rolling engagement with ears 49 on the shaft 40.

In assembling the parts, the cams are so placed as to actuate the rocker arms to ac- 45 tivate the valves at the proper intervals; the shaft 40 being provided with a sprocket 50 that is operatively connected with a sprocket 51 on the drive shaft 19 by means of a chain belt 52; the said sprockets hav- 50 ing a two to one ratio whereby the piston oscillation takes place one for two complete revolutions of the power shaft.

In making the parts, the crank arm 16 of the rocker shaft and crank arms 18 of the 55 drive shaft 19 are so proportioned that the arc through which the rocker arm 16 is carried by a revolution of the shaft 19 will be of the proper length to insure the proper compression of the fuel within the combustion chambers.

I have also provided the housing with a 60 water jacket as shown, having inlet and outlet connections 54—55 whereby water may be circulated about the cylinders for cooling 65 the parts.

The engine is also provided with the usual spark plugs 56 which are preferably ar- ranged in a central position of each explo- sion chamber and may be connected with a timer in any suitable manner.

I also provide the pistons with packing rings 57 to prevent possible leakage be- 70 tween the explosion chambers.

I also prefer to inclose the crank arms 18 and 16 with a housing 59 which may carry 75 a lubricating fluid for automatically oiling the parts contained therein.

Presuming the parts to be so constructed, I will follow the operation of the parts through one complete cycle, presuming that 80 Fig. I shows the parts at a starting point wherein the pistons 6—7 are at the limit of their travel in the direction shown:

The piston 6 has just completed the com- pression stroke with respect to the compart- 85 ment 4, both the exhaust and intake valves communicating therewith being closed, and the fuel being compressed therein.

During the period that the piston is com- pressing the charge within the chamber 4 90 the intake valve of the compartment 4' is opened by the cam action and a charge drawn therein.

During the period that the piston 6 is compressing the charge in the chamber 4, 95 the piston 7 of the rear cylinder working in the same plane with the piston 6 is exhaust- ing a charge from the chamber 5 and com- bustion is taking place within the chamber 5', both the exhaust and intake valves of 100 compartment 5' and the inlet valve of compartment 5 being closed, but the exhaust outlet from chamber 5 being open.

At the completion of the compression stroke of chamber 4, combustion takes place 105 therein, moving the piston 6 to its opposite limit, compressing the charge in chamber 4'; both valves in chamber 4' being closed. During this movement the piston 7 within 110 the rear cylinder is exhausting a burned charge from the chamber 5'; the exhaust valve being open and intake valve closed, and a fresh charge being taken into the chamber 5; the intake valve being open and exhaust closed.

On completion of the foregoing move- 115 ment, the compressed charge in chamber 4' is fired, moving the piston 6 back to its op- posite limit, and exhausting the burned gas from the chamber 4, the exhaust valve being 120 opened and the intake valve closed.

With this movement, the piston 7 com- presses the charge in chamber 5, both valves opening thereto being closed, and a fresh charge being taken into chamber 5'; the 125 intake valve being opened and the exhaust closed.

On completion of this movement, com- bustion takes place in chamber 5, both valves being closed, the piston 7 is moved to the 130

opposite limit to compress the charge in chamber 5' where both valves are closed. During this operation the piston 6 is moved to exhaust the burned gas from chamber 4'; 5 exhaust valve being open and intake valve closed, and a fresh charge being taken into the chamber 4, where the exhaust valve is closed and intake open.

During this movement a charge is compressed in chamber 5' and a fresh charge taken into chamber 4. The burned charge is exhausted from chamber 4' which brings the parts back to the initial point of the cycle.

15 With this arrangement of parts, it is apparent that the valves operate to uncover their respective ports to impart a regular oscillating movement to the piston, which will impart through the connections shown 20 a rotatory movement to a power shaft.

It is also noted that the number of operating parts of the ordinary engine is greatly reduced and a compact and substantial engine provided which may be used as a stationary engine, but is particularly adapted 25 for motor vehicles.

While the engine is shown to comprise but two cylinders I do not wish to limit it to this particular number, nor to the semi-spherical shape shown, as in some cases it 30 may be more practical to make the explosion chambers of greater depth.

It will also be seen that by proper connections the engine may be operated with 35 steam power equally as well as with the combustible fuel.

Having thus described my invention, what I claim as new therein, and desire to secure by Letters-Patent, is:

40 1. The combination with a housing having semi-spherical portions containing independent semi-spherical piston chambers, each of said portions having a protuberance, the said protuberance forming a journal bearing and each of said semi-spherical 45 portions comprising water jackets, a rocker shaft journaled in the housing, pistons fixed to said rocker shaft and operable in the

separate chambers, a crank shaft journaled in the protuberance bearings, and a rod 50 connecting the rocker shaft and crank shaft.

2. The combination with a piston housing comprising semi-spherical piston chambers arranged in longitudinal alinement and having longitudinally alining bearing seats 55 therein, a rocker shaft mounted in said seats, pistons fixed to said shaft and projected into said chambers, a cover plate seated over said piston chambers and attached to said housing and having a longitudinal channel seat inclosing said rocker shaft; said housing and cover plate being water jacketed, and intake and exhaust valves opening through the cover plate into 60 said piston chambers at both sides of said 65 pistons.

3. The combination with a piston housing comprising semi-spherical piston chambers arranged in longitudinal alinement and having longitudinally alining bearing seats 70 therein at the open side of the chambers and longitudinally alining protuberances extending from the base of the housing, forming journal bearings, a rocker shaft mounted in said bearing seats, a cover plate 75 mounted on said housing having longitudinal channel seats on its under face for receiving and inclosing said rocker shaft and having standards thereon, a cam shaft revolvably mounted in said standards in parallel alinement with the rocker shaft, pistons fixed on the rocker shaft and projecting into said chambers in longitudinal alinement relative to the shaft, exhaust and intake valve mechanism operatively connected 80 with the cam shaft mounted on said cover and opening therethrough to the piston chambers at both sides of said pistons, a crank shaft revolvably carried in the housing protuberances, an actuating rod connecting the rocker shaft with the crank shaft and a belt operatively connecting the crank shaft with the cam shaft, for the purpose set forth.

In testimony whereof I affix my signature. 85
BYRON O. SHORT.
